UNITED STATES PATENT OFFICE.

HERMAN A. BINDEMAN, OF CHICAGO, ILLINOIS, ASSIGNOR TO THE UNION WIRE MATTRESS COMPANY, OF ILLINOIS.

WIRE-UNWINDING APPARATUS.

SPECIFICATION forming part of Letters Patent No. 377,422, dated February 7, 1883.

Application filed July 8, 1887. Serial No. 243,749. (No model.)

To all whom it may concern:

Be it known that I, HERMAN A. BINDEMAN, a citizen of the United States, residing at Chicago, in the county of Cook and State of Illinois, have invented certain new and useful Improvements in Wire-Unwinding Apparatus, which I desire to protect by Letters Patent of the United States, and of which the following is a specification.

10 *My invention relates to mechanism for unwinding wire from spools in connection with wire-coiling looms and for similar purposes, in which the liability of the wire to become kinked is obviated.*

15 *Figure 1, Sheet 1, of the drawings shows a coiling-loom in perspective, or as much of it as is necessary to illustrate my invention; and Figs. 2, 3, and 4, Sheet 2, show sectional portions of the improvement.*

20 *Like letters and figures indicate like parts both in the drawings and specification.*

A is the loom-standard; B, the table upon which the coils C are projected as formed by the machine. The machine is driven by a 25 belt upon pulley D, having a friction-pinion, d, which acts upon the inner face of hand-wheel E, secured upon the shaft of one of the feed-rollers of the machine. (Not shown.) The wire is supplied to the coiling machinery 30 from the stationary forms F, from which it

unwinds around the enlarged heads and passes up through tubes G, which are supported loosely in stands G', as shown in Figs. 1, 2, and 35 3 of the drawings of Sheet 2, the upper end of said tube having collars upon it, as more clearly seen in Fig. 4, leaving the tubes free to gyrate, as shown in dotted lines, at their lower ends around the forms F as the wire unwinds and is drawn up through the tubes over the grooved

40 rollers H and around rollers I and J to the feed-rollers of the machine. Thus the wire is supplied from these forms F or stationary spools without any rotation of the spools, as has hitherto been the practice, and the advantage of thus unwinding the wire is very material. First, it saves the power required to

start often heavily-loaded spools as each coil is formed; secondly, it avoids the momentum acquired by the spools, which causes them to continue to rotate after a coil is completed, and thus unwinding the wire and causing it to tangle in the interim between the stopping for the last and starting for the next coil; thirdly, the strain exerted upon the wire in suddenly starting the rotating spools causes it to vary the pitch in coiling, and especially when two wires are run together, as in the machine shown, supplied from spools often of unequal weight, they are very apt to coil unlike and run apart, and frequently to hop out of the web, thus rendering it necessary to cut off and waste more or less of the imperfect coils of wire, whereas the unwinding of the wire from a stationary form or spool exerts comparatively no resistance upon it and supplies it to the coiler at a much more even tension, thus causing it to coil much more perfectly, and consequently with much less waste of wire; fourthly, the coiling-loom can be run much faster, because there are no heavy spools to start and stop, which becomes more difficult as the speed is increased and can hardly be done successfully at a high rate of speed.

My improvement is, of course, as applicable to a machine for coiling one wire at a time as 75 for two or more wires.

Having thus described my invention, what I claim as new, and desire to secure by Letters Patent, is—

In a wire-coiling machine, a stationary form 80 or spool for holding the wire, in combination with a tube or guide through which the unwinding wire is conducted, that is so connected at its upper end as to permit of a gyratory movement of the lower end, and the said lower end adapted to move in an orbit about the head of the spool, substantially as shown and described.

HERMAN A. BINDEMAN.
